(57) **CLAIM**

The ornamental design for a patient assistance device, as shown and described.

DESCRIPTION

FIG. 1 is a front perspective view of the patient assistance device of the present invention in a closed position;

FIG. 2 is a front elevation view thereof;

FIG. 3 is a back elevation view thereof;

FIG. 4 is a right side elevation view thereof, the left side elevation view being a mirror image thereof;

FIG. 5 is a top plan view of the patient assistance device of the present invention in an opened position; and,

FIG. 6 is a bottom plan view thereof.

The broken line drawing depicts stitching, which forms part of the claimed design.
